UNITED STATES PATENT OFFICE.

JOHN T. BLUFF, OF SEATTLE, WASHINGTON, ASSIGNOR OF TWO-THIRDS TO
JOSEPH McBURNEY AND JACOB BECKER, OF SEATTLE, WASHINGTON.

COMBINED DINNER-PAIL AND COOKER.

SPECIFICATION forming part of Letters Patent No. 714,633, dated November 25, 1902.

Application filed February 14, 1902. Serial No. 93,991. (No model.)

To all whom it may concern:

Be it known that I, JOHN T. BLUFF, a citizen of the United States, residing at Seattle, in the county of King and State of Washington, 5 ton, have invented certain new and useful Improvements in a Combined Dinner-Pail and Cooker, of which the following is a specification, reference being had therein to the accompanying drawings.

10 This invention relates to improvements in the class of articles known as "dinner-pails," wherein I have combined a cooking oil-stove and a lamp, which are designated for use separately for the different uses for which 15 they are adapted or for use in combination.

It consists of a pail provided with food holding and cooking trays or pans, a cooking-lamp positioned beneath the pans in the bottom of the said pail, another lamp for supporting light and also acting as a supplemental heater, and in certain details of construction and combination of parts hereinafter described, and pointed out in the claim.

20 In the accompanying drawings, Figure 1 is a central vertical section of a dinner-pail embodying my invention. Fig. 2 is a plan view of the pail proper with the cover and inner trays and stove removed; and Figs. 3 and 4, respectively, are perspective views of tray-pans *g* and *h* shown in Fig. 1.

The letter *a* indicates the pail proper, but which in order to avoid confusion I will designate as the "case," having an attached bail *b* and is preferably cylindrical in form. Integral with and extending inwardly from the rim of said case is a shelf *c*, and a reflector *d*, substantially vertical, provides two compartments *e* and *f*. The shelf *c* is inclined downwardly from the sides of the pail and is 35 provided with an opening. This opening is approximately rectangular and extends inward from the edge of the shelf, whereby the open end thereof will be closed by the adjacent side of the pail when the shelf is secured 40 in position. By this construction the tray *g* when inserted in position will not contact with the reflector *d*.

A tray *g* of similar horizontal cross-section to the opening in the top of compartment *f*, 45 supported by its flanged rim *i*, extends downwardly into said compartment, and another

tray *h*, formed of two integral sections—that is, a lower portion adapted to fit in the aforesaid tray and an upper portion being cylindrical or of similar cross-section to case *a*. The 55 tray *g* and the interfitting part of tray *h* taper from the top down, whereby they are more readily separated and the combustion-gases, coursing beneath and around the sloping sides, more quickly heat the contents to a cooking-point. A lamp-stove *k* is provided in bottom of compartment *f*, of which *k'* designates the wicks, inclosed in burner-tubes *k''*. *l* is a peep-hole in the peripheral wall of the case, whereby the flames of the said lamp-stove are 60 regulated, and closure is made by a sliding gate *m*. *t* is a lens or glass pane mounted in a hinged door *n*, through which a lamp *o* is inserted. Draft and vent holes *p* and *p'*, in proximity to the bottom and top, respectively, 70 of the case, insure a suitable supply of air for combustion as well as the escape of the smoke or gases therefrom. Holes *s* with flanged edges are disposed in the bottom of both of said compartments and designed for candle- 75 sockets, which may be used instead of the aforesaid lamps. *t'* is a cover for the upper tray.

The operation of the device is as follows: The cooking, which would usually consist only 80 in making tea or coffee, is done in the lower tray *g* by means of the lamp-stove *k*, after which its flames may be extinguished and the other lamp lighted, heating the said reflector, from which by radiation the compartment *f* 85 and in turn the trays *g* and *h*, with their contents, are kept warm.

As will be noticed, this device may be used in a variety of ways—namely, for cooking, for keeping the viands warm and free from 90 all danger of burning, and lastly as a lantern—which are advantageous to those employed underground, as in mines, or, in fact, to any one working on a night-shift.

Having thus described my invention, what 95 I claim as new, and desire to secure by Letters Patent, is—

The combination with a pail provided at its upper edge with an inwardly-projecting downwardly-inclined shelf provided with an opening extending inward from its edge, of a tray provided at its upper edge with an outwardly-

projecting flange, said tray arranged in the opening of the said shelf and supported therein by its flange, a removable section of the same diameter as the pail provided with a 5 horizontal lower face, a downwardly-extending tray formed integral with the lower face of said section and projecting into the first-named tray, a cover for the said removable section, a heating means, and a reflector se-

cured to the side of the said pail and arranged beneath the shelf thereof, substantially as described.

In testimony whereof I affix my signature in presence of two witnesses.

JOHN T. BLUFF.
